Primary Examiner — Natasha Vujcic(74) *Attorney, Agent, or Firm* — Staas & Halsey LLP(57) **CLAIM**

The ornamental design for a lamp, as shown and described.

DESCRIPTION

1. Lamp

1.1 : Perspective

1.2 : Perspective

1.3 : Front

1.4 : Left

1.5 : Top

1.6 : Right

1.7 : Bottom

The broken lines in the drawings illustrate portions of the lamp which form no part of the claimed design.

The dot-dash broken line break lines in the drawings indicate that the appearance of any portion of the lamp between the break lines forms no part of the claimed design.
